HIS ATTORNEY.

UNITED STATES PATENT OFFICE

FREDERICK S. McCULLOUGH, OF EDGEWOOD BOROUGH, PENNSYLVANIA

ELECTRICAL DISCHARGE DEVICE

Application filed April 8, 1929. Serial No. 353,396.

My invention relates to devices operating by electrical discharge, such as triodes and electronic rectifiers, and particularly to such devices handling large power, its broad purpose being to increase the rating at which such apparatus may safely be operated.

An object of my invention is to prevent cracking of the seals of electrical discharge devices, owing to differential thermal expansion.

Another object of my invention is to prevent the liberation of adsorbed gases from the seals of such devices, either by the action of heat conducted to the seals or by accidental electronic or ionic bombardment.

My invention possesses other objects and valuable features, some of which will be set forth in the following description of my invention which is illustrated in the drawing forming part of the specification. It is to be understood that I do not limit myself to the showing made by the said description and drawing, as I may adopt varying forms of my invention within the scope of the claim.

The capacity of electronic apparatus, like that of most electrical devices, is limited by the heat evolved in the apparatus when under load. The effect of this evolution of heat, with its consequent temperature rise, may be manifested in different ways. The electrodes themselves may be destroyed, the envelop may be melted, the seals may crack, or the vacuum may be so lowered by the liberation of adsorbed gases as to render the device inoperative.

The advent of water-cooled anodes has greatly increased the possible maximum power for which such apparatus may be constructed, and where they are used they practically eliminate the first two causes of failure. This makes the seals the most vulnerable part of the device, for beside being subject to failure by cracking, they are the areas where adsorption of gas is most likely to occur, and the most difficult to free of gas which has been adsorbed.

Owing to the small absorption of power in the grid circuit of a triode, the grid support and its seal might be expected to re-

main at a relatively low temperature and to give little trouble even without resort to special precautions. As regards amplifying triodes, where the grid is operated with a strong negative bias at all times, this is in general true. Where a triode is used as an oscillator, however, the grid swings positive during a portion of the cycle, and during this period not only the grid but also its support and the glass of the seal itself are subject to electronic bombardment. This entails an evolution of heat with the attendant troubles already set forth, and in large triodes the grid support and its seal may be the "hot spot" which sets the limit to power output. My invention serves to increase the power limit thus set.

Referring to the drawing, the single figure is an axial longitudinal section of the device of my invention as embodied in a power triode.

Broadly stated, my invention comprises a shield positioned to intercept electrical bombardment of the envelop, and particularly of the seal of an electrical discharge device. The shield is preferably carried on the support for one of the electrodes of the device, and this support is provided with a devious passage for conducting a cooling fluid. The electrode may therefore be operated at a relatively high temperature without endangering the seal.

Describing in detail one embodiment of my invention, a substantially cylindrical vitreous envelop 6 encloses a water-cooled anode 7 and a filamentary cathode 8, arranged as described in my co-pending application, Serial No. 286,370, filed June 18, 1928.

Projecting through the end of the envelop is a tubular support member 9, whose inner end is provided with a closure 11. An annular groove 12 encircles the support, and is bridged by a thin metal sleeve 13, welded at one end to the support, to which sleeve the envelop is joined by the seal 14 as is described in my co-pending application, Serial No. 269,439, filed April 12, 1928.

Fixed at the end of the support 9, and in close thermal contact therewith, is a disk-shaped shield 16, so positioned as to inter-

cept electronic bombardment directed to the seal from the electrodes or the inter-electrode space. The grid 17, which is preferably of an easily degasified material such as molybdenum, is carried by wires 18 which are fixed to the shield.

A devious passage, in this embodiment a folded passage, is provided within the support for conducting a cooling medium, which may be any suitable fluid such as water, oil or air. A plug 19, mounted on the outer end of the support, carries a tube 21 which extends thru the plug and concentrically with in the support nearly to the closed inner end. An upset 22 is provided at the outer end of the tube to facilitate a hose connection, and a similarly upset hose nipple 23 extends laterally thru the side of the support. Either thermo-syphon or pressure methods may be used to circulate the cooling fluid.

It will be seen that this arrangement provides almost perfect protection for the seal. The close thermal contact between the shield and the cooled support permits a rapid transfer of heat, thus keeping the shield itself cool and preventing the heating of the seal by radiation from the shield. Conduction of heat from the grid is not so rapid, but since it cannot heat the shield by radiation it may be permitted to operate at a relatively high temperature, and the cooled support prevents the transfer of this temperature to the glass.

I claim:

A device of the character described, comprising an envelope, an anode within the envelope, a cathode within the envelope, a post passing through the envelope having a fluid circulating passage therein, a shield carried by the post within the envelope, and a grid electrode within the envelope carried by and supported on the shield, the shield being of a diameter greater than the diameter of the grid and approximately spanning the distance between the anode and cathode.

In testimony whereof, I have hereunto set my hand.

FREDERICK S. McCULLOUGH.
